Earl B. Lear.
BY *Herbert G. Odell*
HIS ATTORNEY.

UNITED STATES PATENT OFFICE.

EARL B. LEAR, OF PHILLIPSBURG, NEW JERSEY, ASSIGNOR TO INGERSOLL-RAND COMPANY, OF JERSEY CITY, NEW JERSEY, A CORPORATION OF NEW JERSEY.

AIR-FEED CONTROL.

Application filed September 18, 1925. Serial No. 57,067.

This invention relates to fluid actuated rock drills, but more particularly to means for controlling the feed element of a stoper type drill.

The type of drill for which the present invention is contemplated is used chiefly for overhead drilling and is provided with an air feeding element for holding the drill steel firmly against the work. At times the steel becomes stuck in the drill hole and by releasing a portion of the pressure fluid from the feeding cylinder, the drill may be withdrawn somewhat until the steel has again been loosened by the blows of the hammer piston.

The objects of the invention are to control the air feeding element of a rock drill in a simple and convenient manner and to enable the air feed control to be held in adjusted position by mechanical means.

Other objects will be in part obvious and in part pointed out hereinafter.

The invention consists of the combinations of elements, features of construction and arrangement of parts having the general mode of operation substantially as herein-after described and more particularly pointed out in the appended claims and illustrated in the accompanying drawings, in which—

Figure 1 is an elevation, partly in section, of a stoper type rock drill equipped with an air feed control constructed in accordance with the practice of the invention,

Figure 2 is an enlarged detail view, partly in section, of a portion of the rotation handle showing the valve in releasing position, and

Figure 3 is a transverse view, partly in section, taken through Figure 1 on the line 3—3 looking in the direction of the arrows with the valve in closing position.

Referring to the drawings, A indicates a cylinder supported at its front end by a front head B and in this instance secured thereto by spring pressed side bolts C. A drill steel D is supported by the front head B and is adapted to receive the blows of the hammer piston (not shown) reciprocating within the cylinder A.

Drills of the type illustrated in the drawings may be rotated either manually or by mechanical means. In this instance a motor (not shown) is indicated, and is provided with a casing E secured to the back end of

the cylinder A by bolts F. A head block G forms a closure for the motor and also serves as a valve chest for a suitable throttle valve (not shown) whereby the pressure fluid entering the head block from a suitable source of supply may be admitted to the various pressure fluid actuated elements of the drill. A lever H may be provided for manipulating the throttle valve.

In order to advance the drill in accordance with the penetration of the drill steel D into the work, a feeding element is provided. The feeding element in this instance is the element to be controlled and comprises a feed cylinder J secured to the head block G in any suitable manner and has a piston K supported by a piston rod L. The piston rod L extends through the free end of the cylinder J and carries a rock engaging pointer O which supports the drill and is adapted to penetrate the rock to prevent lateral movement of the drill.

In order to prevent rotation of the drill with the drill steel, a handle P is secured to the head block G and has a projection Q at its free end extending preferably at right angles to said handle. In the present instance the handle P is of sufficiently large cross sectional area to enable an oil reservoir R to be formed longitudinally therethrough. The oil reservoir R is provided with a passage S which preferably communicates with the throttle valve so that when the drill is in operation, a portion of the pressure fluid will pulsate into the reservoir and carry the oil in the form of vapor to the various movable parts of the drill.

In accordance with the practice of the invention, a passage T communicating at its inner end with the cylinder J through a passage U formed in the head block is formed longitudinally through the handle P and terminates at its other end at a point near the juncture of the handle P and the projection Q. The passage T is constantly in communication with the feeding cylinder J so that when pressure fluid is admitted into the feeding cylinder a portion thereof will also pass into the passage T.

In order to control the outlet end of the passage T a valve chamber V is formed transversely through the projection Q to receive a reciprocatory valve W. In this instance, the valve W is provided with a removable valve head X preferably of small-

er diameter than the valve W and which extends beyond the valve chest V to bear against a face Y of a cam Z . The cam Z is preferably in the form of a collar and in this instance carries a lever b whereby the cam may be manipulated. In order to limit rotative movement of the cam on the projection Q , a stop c is secured to the projection to cooperate with the ends of an arcuate slot d formed in the cam.

To the end that the cam Z may be held in adjusted position, a series of teeth e are formed in the bore of the cam to cooperate with a ratchet plunger f slidable in the valve and the valve chest. The teeth e are so arranged with respect to each other that various degrees of opening of the valve may be obtained, depending upon the extent of rotation of the cam. In this instance a spring g is arranged within the valve W and the ratchet plunger f to constantly force the valve and said ratchet plunger outwardly against the cam. In order to provide for the escape of pressure fluid from the valve chest whenever the valve W is opened, undercuts or recesses h are formed in the top and bottom faces of the cam preferably adjacent the head X. A sleeve j forming a grip for the operator is in this instance screwed on the projection Q and forms a bearing for the cam Z to prevent endwise movement of said cam. Any suitable means may be provided for preventing unscrewing of the sleeve j. In this instance a lock washer k is inserted between the end of the projection Q and a shoulder o formed in the sleeve j.

If during the operation of the drill, the drill steel D encounters a soft spot in the rock, the feeding pressure is preferably reduced to prevent jumping of the drill. To so reduce the feeding pressure the cam Z may be rocked about the projection Q to open the valve W and allow some of the pressure fluid to bleed from the feeding cylinder to the atmosphere. When the cam Z is rocked to one or the other of the releasing positions, the ratchet plunger F will engage one of the teeth e in the cam and due to the action of the spring g will continue to hold the cam in adjusted position until the cam is again actuated by the operator.

By this form of construction the valve will be held in adjusted position so that a uniform and continuous release of pressure fluid from the feeding cylinder may be obtained. This is a desirable feature in devices of this type for the reason that it is extremely difficult for the operator to hold the releasing device in one particular position owing to the extreme vibration set up during the operation of the drill.

I claim:—

1. In a rock-drill the combination with an element to be controlled, of a handle hav-

ing a projection at an angle therefrom, a passage through the handle leading from the element to be controlled to the projection, a valve in the projection controlling said passage for regulating the exhaust of pressure fluid from the element to be controlled, an oscillatory cam in the form of a sleeve encircling the periphery of said projection for opening the valve, and means 75 slidable in the valve to engage the cam for holding said cam in adjusted position. 70

2. In a rock drill the combination with an element to be controlled, of a handle having a projection at an angle therefrom, a passage through the handle leading from the element to be controlled to the projection, a valve slideable transversely through the projection to control the passage for regulating the exhaust of pressure fluid from the element to be controlled, an oscillatory cam in the form of a sleeve encircling the periphery of the projection for opening the valve, ratchet teeth on said cam, and a ratchet plunger slideable in the valve to cooperate with the teeth for holding the cam in adjusted position. 80 85 90

3. In a rock drill the combination with an element to be controlled, of a handle having a projection at an angle therefrom, a passage through the handle leading from the element to be controlled to the projection, a valve slideable transversely through the projection to control the passage for regulating the exhaust of pressure fluid from the element to be controlled, a removable head in said valve, an oscillatory cam in the form of a sleeve encircling the projection, and slideable on the said valve head for opening the valve, ratchet teeth carried by the cam, a ratchet plunger slideable in the valve to cooperate with the teeth for holding the cam in adjusted position, and a spring in the valve and the ratchet plunger for holding said valve and ratchet plunger in constant contact with the cam.

4. In a rock drill the combination with an element to be controlled, of a handle having a projection at an angle therefrom, a passage through the handle leading from the element to be controlled to the projection, a valve 115 slideable transversely through the projection to control the passage for regulating the exhaust of pressure fluid from the element to be controlled, a removable head in said valve, an oscillatory cam in the form of 120 a sleeve encircling the projection and slideable on the said valve head for opening the valve, ratchet teeth carried by the cam, a ratchet plunger slideable in the valve to cooperate with the teeth for holding the cam in 125 adjusted position, a spring in the valve and the ratchet plunger for holding said valve and ratchet plunger in constant contact with the cam, and a grip screwed on the projection for manipulating the handle and for 130

preventing endwise movement of the cam.

5. In a rock drill the combination with an element to be controlled, of a handle having a projection at an angle therefrom, a passage leading from the element to be controlled to the projection, a valve slidable transversely through the projection controlling the passage for regulating the exhaust of pressure fluid from the element to be controlled, a ¹⁰ movable head in said valve, an oscillatory cam in the form of a sleeve encircling the projection and slidable on the said valve head for opening the valve, a lever on said

cam, ratchet teeth carried by the cam, a ratchet plunger slidable in the valve to co-¹⁵ operate with the teeth for holding the cam in adjusted position, a spring in the valve and the ratchet plunger for holding said valve and ratchet plunger in constant contact with the cam, and a grip screwed ²⁰ on the projection for manipulating the handle and for preventing endwise movement of the cam.

In testimony whereof I have signed this specification.

EARL B. LEAR.
